ARTIFICIAL LEATHER SHEET OR SIMILAR ARTICLE

Joseph Barash, Peekskill, N. Y.

Application April 8, 1950, Serial No. 9,076

Term of patent 3½ years

(Cl. D87—3)

To all whom it may concern:

Be it known that I, Joseph Barash, a citizen of the United States, residing at Peekskill, in the county of Westchester and State of New York, have invented a new, original, and ornamental Design for an Artificial Leather Sheet or Similar Article, of which the following is a specification, reference being had to the accompanying drawing, forming part thereof.

The figure is a face view of an artificial leather sheet or similar article, showing my new design.

The area within the dotted lines shows one unit of the design. Said design unit is repeated over the artificial leather sheet vertically and horizontally on the drawing.

I claim:

The ornamental design for an artificial leather sheet or similar article, as shown, and described.
JOSEPH BARASH.
